UNITED STATES PATENT OFFICE

2,473,659

INDUSTRIAL TRUCK

Herman C. Musgrave, East Cleveland, Ohio, assignor to Towmotor Corporation, Cleveland, Ohio, a corporation of Ohio

Application June 10, 1946, Serial No. 675,745

10 Claims. (Cl. 214—113)

1

This invention relates to industrial lifting trucks, and more particularly to means carried by said trucks for receiving loads upon their carriage assemblies, for raising and lowering the said assemblies along the masts of said trucks, and for changing the positions of the load-carrying members of said assemblies thereby to facilitate depositing the loads carried thereby in any desired positions and locations. It is the general object of the invention to provide simple and effective power operated mechanism for accomplishing the aforesaid movements of the carriage assemblies and their load-carrying members. A further object of the invention is to enable all of these operations to be readily and effectively controllable by the operator.

A still further and more limited object of the invention is to provide hydraulically operated means whereby a carriage assembly may be raised and lowered along its mast and rotary movement may be imparted to the load-carrying member of said assembly at any point in its elevation by the carriage, thereby to facilitate depositing the load carried thereby in any desired position or location.

In the practice of my invention, the load carrying member of the carriage assembly is rotated by the bight of a cable extending around a sheave which is rigidly secured to the rotating member and the reaches of which cable extend over rollers or pulleys carried by the cross head of the plunger or piston by which the carriage assembly is raised and lowered and the ends are connected to the upper ends of piston rods of jacks whereby, by the depression of either of the latter piston rods, the sheave and the rotatable member of the carriage assembly may be turned in either direction. As thus broadly stated, the cable is operatively connected to the sheave and to the piston rods of the jacks in the manner shown, described and claimed in the application of Paul R. Guerin and myself, Serial No. 610,408, filed August 13, 1945, now Patent No. 2,399,632, granted May 7, 1946.

As an improvement over the construction shown and described in the said application, I have so supported the ends of the reaches of the cable as to enable me to obtain a double amount of lift of the carriage assembly and a double angular movement of the rotatable member thereof for the same length of jack cylinders and pistons that are employed with the construction shown in the aforesaid application.

A still further object of the invention is to provide an improved construction and arrangement

2

of parts whereby the rotatable member of the carriage assembly is mounted for rotation upon the supporting portion of the said carriage assembly.

I accomplish the foregoing objects and other and more limited objects which will be set forth hereinafter in and through the construction and arrangement of parts shown in the accompanying drawings wherein Fig. 1 represents a side elevational view of the front portion of an industrial lifting truck and the mast therefor and showing the carriage assembly and the hoisting mechanism therefor and the means for rotating the load-carrying member of said assembly constructed in accordance with my invention, the position of the carriage when elevated being indicated by broken lines and the front portion of the truck being represented diagrammatically; Fig. 2 a front elevational view of the parts illustrated in Fig. 1 and showing the rotatable load-carrying member of said assembly in its load-receiving position; Fig. 3 a view, similar to Fig. 2, showing the rotatable load-carrying member slightly elevated and tilted whereby a load thereon may be conveniently discharged at a desired angle therefrom, the lifting forks being omitted; Fig. 4 a detail in section taken on the line 4—4 of Fig. 1; Fig. 5 an enlarged central sectional view through the rotatable member of the carriage assembly and the cooperating portion of the supporting member of said assembly; and Fig. 6 a diagrammatic view of the means for controlling and supplying liquid to the auxiliary cylinders of the jacks which constitute part of the means for realizing my invention.

Describing by reference characters the various parts illustrated in the drawings, 10 denotes generally the forward end of the body of an industrial truck, 11 one of the front wheels of the same, and 12 one of a pair of skirt plates of the frame A behind which are located the corresponding arms (not shown) which enable the mast to be tilted from a vertical position. Each of the side members of the mast has secured to the lower portion thereof a hook 13 by which the mast is pivotally supported from a cross bar 14 which in turn may be supported by part of the front driving axle (not shown) in the manner illustrated and described in the patent to E. W. Weaver, No. 2,299,445, issued October 20, 1942.

15 denotes generally the front plate of the supporting member of the carriage assembly from opposite sides of which guide plates 16 project rearwardly and engage the inner surfaces of the

channeled side members B of the mast. These guide plates carry upper and lower rollers 16^a (see Fig. 4) which are adapted to engage the front and rear flanges respectively of the channeled side members of the auxiliary mast in the usual manner, as shown, for instance, in the aforesaid application of Paul R. Guerin and myself.

17 denotes the main hoisting cylinder which is located between the sides of the mast and within which the plunger 18 is mounted, said plunger carrying a cross head 19 at its upper end. The cross head is provided with a pair of ears 20 extending upwardly therefrom and adapted to engage the cross tie 21 which connects the tops of the side members 22 of the auxiliary mast. A yoke 23 is shown as connected to the webs of the channeled members of the main mast and as extending across the rear of the same.

The construction thus far described is substantially identical with that which has been employed by Towmotor Corporation in its production of industrial trucks, and hence needs no further description.

The rotatable carriage member comprises generally a framework consisting of an upper spacer bar 24, vertical side bars 25, centrally located vertical reinforcing bars 26, with an upper cross plate 27 and a lower cross plate 28 connected to the vertical bars 25 and 26.

29 denotes a fork-supporting bar which is mounted in aligned apertures provided therefor in the vertical side and reinforcing bars adjacent to the spacer bar 24. 30 denotes the vertical arms of lifting forks, the lower forwardly projecting ends of which are shown at 31. The upper ends of the fork arms 30 are provided with apertures whereby they are slidably mounted on the bar 29, and may be retained in any desired adjusted position with respect to said bar by means of U-shaped yokes 32, the legs of which are adapted to be inserted through openings 24^a in the top of the spacer bar 24, with their legs embracing opposite sides of the upper ends of the fork arms.

The manner in which the rotatable carriage member is supported for rotation on the supporting member will now be described: 33 denotes a bearing shaft which is secured, as by welding, to the front plate 15 of the supporting member of the carriage assembly and on which there is mounted the inner race 34 of a tapered roller bearing comprising an outer race 35, a cage or cup 36 and rollers 37. The cage or cup is secured, as by welding, to the wall of an opening provided therefor in a large sheave 38, the front of the bearing being provided with a washer 39. The cage or cup 36 is also secured, as by welding, to the cross plate 27.

Cylindrical anti-friction blocks or plugs 40 are inserted within seats provided therefor in the rear of the body of the sheave 38 and project rearwardly beyond the rear surface thereof and engage with their rear faces an annular bearing plate 41 which is secured to the front of the front plate 15 of the supporting member. These blocks may be made of material known to the trade as "Powdiron," consisting of fine iron particles united by compression and impregnated with lubricant. Openings 40^a extend from the front of each block through the sheave 38, providing means whereby the blocks may be removed and replaced.

42 denotes the cylinders of a pair of jacks which are conveniently located within the lower portion of the mast assembly and the lower ends of which may be pivotally supported in any con-

venient manner from the base of the mast assembly, as indicated at C, Fig. 3. Each of the cylinders is provided with a piston rod 43 extending through the top thereof, each of the said piston rods being provided at its upper end with a shackle comprising a pair of links 44 pivotally connected at their lower ends to the top of each piston rod and each pair of links supporting at their upper ends a journal pin 45 on which is mounted a sheave 46.

47 denotes brackets conveniently secured to a vertically non-reciprocable portion of the truck, as by being welded to the cylinder 47. Eye bolts 48 extend through apertures provided therefor in the ends of the bracket arms 47 and are longitudinally adjustable with respect to said brackets by means of nuts 49 threaded thereon and located above and below the respective bracket arms.

The ends 50 of the cable by which the rotatable member of the carriage assembly is operated are connected to the eyes 48^a of the eye bolts as by means of eyes on eye bolts 51 with which hooks the said cable ends have a swivel connection 51^a. The reaches of the cable extend around the respective sheaves 46 and thence upwardly around the sheaves 52 rotatably mounted on the cross head 19 and thence downwardly along the inner surfaces of guide sheaves 53 mounted upon roller bearings 54 on bearing shafts 55 extending through openings provided therefor in the upper end of the front supporting member 15, the bearing shafts being provided at their rear ends with threads for the reception of nuts 56. The guide sheaves are positioned in proximity to the upper peripheral portion of the main sheave and are spaced equidistantly from a vertical plane extending through the center of the bearing shaft 38. The distance between the bearing shafts 55 is materially less than the diameter of the sheave 38 whereby the cable is caused to exert a strong frictional grip upon the groove of the latter sheave.

57 denotes a reinforcing plate welded onto the bottom of the cross plate 28 and serving, jointly with the said cross plate, to support U-bolts 58 the upper legs of which extend through apertures provided therefor in the main sheave and in the reinforcing plate and the cross plate 28 while the lower legs extend through the said reinforcing plate and the plate 28, with the cable gripped against the reinforcing plate by the looped ends of the bolts. The outer ends of the legs are threaded and provided with nuts 59. The U-bolts serve to clamp the lower peripheral portion of the main sheave and the portion of the cable within the corresponding portion of the groove of the said sheave against movement with respect to the rotatable member.

The lower portion of the front supporting member 15 is semi-circular, its periphery lying within the periphery of the sheave 38, while its upper end is approximately semi-hexagonal in shape.

60 denotes the casing for a double valve assembly from which pipe 61 extend to the tops of the cylinders 42, the bottoms of the cylinders being connected by an equalizer pipe 62.

With the parts constructed and arranged as described, the operation will be readily understood. With the piston rods 43 elevated to their full extent, the rotatable member of the carriage assembly will be supported in load-receiving position; that is to say, with the forks 31 extending horizontally from the lower ends of the said member. With the piston rods in this position, the carriage, together with the load upon the

forks, can be raised by supplying operating fluid to the main cylinder 17. Assuming, however, that it is desired to discharge the load at any desired point in the elevation of the carriage assembly, the double valve assembly, indicated at 60 in Fig. 6, will be operated to supply fluid under pressure through either of the pipes 61 to the top of the appropriate cylinder 42, the fluid displaced from either cylinder by the descent of the piston therein being delivered into the bottom of the opposite cylinder through the equalizing pipe 62. The carriage assembly having been lifted by the piston or plunger 18 to the desired height, the rotatable member may thereafter be rotated by the pistons of the jacks by relieving the pressure on top of the piston in one of said cylinders and by applying pressure to the top of the piston in the other of said cylinders.

It will be noted that the cable by which the rotatable carriage member may be tilted can also serve the function of imparting what is known as "free lift" to the carriage assembly, without operating the main plunger or piston 18 and without tilting the rotatable member thereof by depressing equally the pistons 43 in the cylinders 42; and it can also exercise the function of rotating the load carrying member of the carriage assembly at any desired point to which it may be elevated either by the pistons 43 or by the plunger or piston 18. Still further, due to the fact that the ends of the cable, after having been secured to the vertically non-reciprocable part of the truck, are rove around the sheaves 46 before being passed over the sheaves 52 and thence around the main sheave, the lifting movement, as well as the tilting movement, of either or both piston rods 43 will be multiplied twice in respect to the lifting or tilting movement imparted to the cable by the said piston rod or rods.

For convenience of description, the rotatable member and the main sheave therefor have been assumed to occupy the positions shown in Fig. 2, and the terms "top" and "bottom" and "upper" and "lower" have been employed in defining the relative positions of these parts but without any intention thereby to limit the rotary member and the sheave to the particular positions there shown.

Having thus described my invention, what I claim is:

1. In an industrial truck, in combination with the front portion of the frame thereof and a substantially vertical mast supported thereby, a carriage assembly comprising a supporting member slidably mounted upon the mast and a rotatable member mounted for rotary movement upon and with respect to the said supporting member, a sheave secured to the said rotatable member with its axis of rotation coincidental with the axis of rotation of said rotatable member, and means for imparting rotary movement to the said rotatable member, the said means comprising a pair of cylinder and piston rod elements, one of the elements of each pair being movable with respect to the other element of each pair, a guide carried by each of the movable elements of each pair of elements, pulley means supported on said carriage assembly and disposed above said guides and sheave and a flexible operating member having its ends secured to a non-reciprocable portion of the truck above said guides and below said pulley means and extending thence about the respective guides and about the respective pulley means with the bight of the said flexible member

extending around and having a driving connection with a portion of the aforesaid sheave.

2. In the industrial truck set forth in claim 1, means for raising and lowering the carriage assembly independently of said cylinder elements and piston rod elements.

3. In the industrial truck set forth in claim 1, a main hoisting cylinder element and a plunger element therein, one of said elements being reciprocable with respect to the other and connected to said carriage assembly, the said reciprocable element supporting the pulley means.

4. In the industrial truck set forth in claim 1, the mast comprising a main mast and an extensible mast mounted for sliding movement upon the main mast, a main cylinder and a plunger therein, and a cross head on said plunger said pulley means being mounted on said cross head, the cross head being adapted by the elevation of the plunger to elevate the extensible mast and the carriage assembly.

5. In an industrial truck, in combination with the front portion of the frame thereof and a substantially vertical mast supported by the said portion of the frame, a carriage assembly comprising a supporting member slidably mounted upon said mast, a journal secured to the said supporting member and projecting forwardly therefrom, an anti-friction bearing rotatably mounted upon the forwardly projecting portion of said journal and comprising inner and outer race members, a sheave having a central opening for the reception of the outer race member of said bearing and secured thereto, a load carrying member located forwardly of the sheave and also secured to the said sheave, a main cylinder and a plunger movable in said cylinder having a cross head provided with a pair of rotatable supporting members, a flexible member having its bight extending about the lower portion of said sheave and around and about the upper portions of said circular supporting members, and reciprocable means engaging portions of the said flexible member whereby rotary movement may be imparted to the said sheave and the rotatable carriage member.

6. In an industrial truck, in combination with the front portion of the frame thereof and a substantially vertical mast supported by the said portion of the frame, a carriage assembly comprising a supporting member slidably mounted upon said mast, a rotatable load carrying member mounted for rotary movement upon and with respect to the supporting member, a sheave secured to the rotatable member with its axis of rotation coincidental with the axis of rotation of the said rotatable member, an annular bearing plate on the front of the said supporting member concentric with the center of said sheave, anti-friction blocks on the rear of said sheave and engaging the front surface of the said annular plate, a flexible operating member having its bight extending around a peripheral portion of the said sheave, and a pair of reciprocable members carried by the truck and means carried by the said reciprocable members for engaging portions of the flexible member.

7. In the industrial truck set forth in claim 6, means for anchoring the ends of the flexible member to a non-reciprocable portion of the truck, guides carried by the said reciprocable members and in engagement with which the reaches of the flexible member extend, and rotatable guiding and supporting members interposed between the

guides and the sheave and about which the reaches of said flexible member extend.

8. In an industrial truck, in combination with the front portion of the frame thereof and a substantially vertical mast supported by the said portion of the frame, a carriage assembly comprising a supporting member slidably mounted upon said mast, a rotatable member mounted for rotary movement upon and with respect to the supporting member, a sheave secured to the said rotatable member with its axis of rotation coincidental with the axis of rotation of said rotatable member, a flexible operating member having its bight extending about the lower portion of the said sheave and operating means engaging portions of the said flexible members for imparting rotary movement to the sheave and to the rotatable supporting member, a reinforcing plate secured to the rear surface of the rotatable member with its upper portion intersecting the lower rear portion of the sheave and extending below the said sheave, and a pair of U-bolts each receiving within the bend thereof a portion of the cable extending about the lower portion of the sheave, the upper branch of each of said bolts extending outwardly through the lower portion of the sheave, the reinforcing plate, and the lower portion of the rotatable carriage member and the lower branch of each bolt extending through the reinforcing plate and the lower portion of the rotatable carriage member, and nuts mounted upon the outer ends of said bolts.

9. In an industrial truck, in combination with the front portion of the frame thereof and a substantially vertical mast supported by the said portion of the frame, a carriage assembly comprising a supporting member slidably mounted upon said mast, a rotatable member mounted for rotary movement upon and with respect to the supporting member, a main sheave secured to the said rotatable member with its axis of rotation coincidental with the axis of rotation of said rotatable member, journals carried by the supporting member adjacent to the top of said sheave, the distance between the said journals being materially less than the diameter of the said sheave, a guide sheave mounted upon each of the said journals with its guide groove in alignment with the groove of the main sheave, a flexible member having its

bight extending about the lower portion of the main sheave and about the inner portions of the guide sheaves, and reciprocable members carried by the said truck for engaging portions of the said flexible member whereby rotary movement may be imparted to the said main sheave and to the rotatable carriage member.

10. In an industrial truck, in combination with the front portion of the frame thereof and a substantially vertical mast supported by the said portion of the frame, a carriage assembly comprising a supporting member slidably mounted upon said mast, a rotatable member mounted for rotary movement upon and with respect to the supporting member, a main sheave secured to the said rotatable member with its axis of rotation coincidental with the axis of rotation of said rotatable member, journals carried by the supporting member adjacent to the top of said sheave, the distance between the said journals being materially less than the diameter of the said sheave, a guide sheave mounted upon each of the said journals with its guide groove in alignment with the groove of the main sheave, a main cylinder and a plunger movable in said cylinder having a cross head provided with a pair of rotatable supporting members, a flexible member having its bight extending about the lower portion of said sheave and about the inner portions of the guide sheaves and thence about the upper portions of said circular supporting members, and reciprocable means engaging portions of the said flexible member whereby rotary movement may be imparted to the said main sheave.
